[57] **CLAIM**

The ornamental design for a rigid tonneau cover with integral tool box, as shown as described.

DESCRIPTION

FIG. 1 is a perspective view of a rigid tonneau cover with integral tool box showing our new design, shown in its position of use;

FIG. 2 is a perspective view of the rigid tonneau cover with integral tool box of FIG. 1 with the cover of the tool box portion shown in open position;

FIG. 3 is a top view of the rigid tonneau cover with integral tool box of FIG. 1;

FIG. 4 is a left side view of the rigid tonneau cover with integral tool box of FIG. 1, the right side being a mirror image thereof;

FIG. 5 is a bottom view of the rigid tonneau cover with integral tool box of FIG. 1;

FIG. 6 is a front view of the rigid tonneau cover with integral tool box of FIG. 1;

FIG. 7 is a back view of the rigid tonneau cover with integral tool box of FIG. 1; and,

FIG. 8 is a perspective view of the rigid tonneau cover with integral tool box of FIG. 1 with the back cover portion shown in open position.

The broken line showing of environment is for illustrative purposes only and forms no part of the claimed design.
